UNITED STATES PATENT OFFICE

RAUL PATERAS PESCARA, OF PARIS, FRANCE

IGNITION DEVICE FOR AIR COMPRESSORS

Application filed April 6, 1927, Serial No. 181,555, and in France April 9, 1926.

My invention relates to air compressors of the type in which two pistons are driven directly by internal combustion, said pistons being synchronized mechanically and particularly to the ignition of the explosive mixture driving said pistons.

The device forming the subject of the present application is particularly adapted to be used with the type of compressor disclosed 10 in my co-pending applications, Serial No. 177,938 filed March 24, 1927; and Serial No. 177,939 filed March 24, 1927, respectively.

One of the objects of the invention is to provide an ignition device for an apparatus 15 of the character indicated which shall assure igniting of the explosive mixture in the cylinder after its preliminary compression and at the time the pistons are near the end of their stroke during normal operation of the apparatus.

Another object of the invention is to provide a means for automatically rendering the air compressor inoperative when the compressed air in the storage tank of the apparatus rises to its normal value and for automatically rendering said air compressor operative again when the pressure falls below its normal value.

Still another object of the invention is to 30 maintain the operation of the pistons while operating at no load by igniting the explosive mixture in the motor cylinder between the pistons only when the pressure of said explosive mixture due to its compression shall 35 have attained a certain predetermined value and in such a manner that the energy developed by the subsequent combustion will be sufficient to assure the replacement of the burned gases by a new charge of explosive mixture.

Other objects of the invention will be obvious to those skilled in the art in the following specification when taken with the accompanying drawing in which—

45 Fig. 1 represents a diagrammatic detail view of my device partly in section on a large scale;

Fig. 2 is a broken section through the distributor taken on the line 2—2 of Fig. 1;

50 Fig. 3 is a development of the surface of

the periphery of the distributor showing the arrangement of the brushes with respect to the distributor contacts; and

Fig. 4 is a diagram showing my improved ignition device as applied to a compressor; 55

It will be remembered that in the co-pending applications, above mentioned, the compressors were provided with a synchronizing mechanism with an oscillating member which turned through less than a complete revolution during each oscillation. This oscillating member provides the driving means for the device forming the subject of the present application.

Referring to the drawing, Fig. 4 shows 61 diagrammatically a compressor similar to the type above mentioned represented generally at A provided with direct driven, substantially free-flying compressing pistons C each fitted in a compressing cylinder D provided with an air outlet a. Said pistons C are interconnected with a synchronizing device B of the oscillatable type requiring a relatively small amount of power for its operation.

Only the essential elements of the compressor A necessary for an understanding of the operation of my improved ignition device have been illustrated since the details thereof are fully disclosed in my copending applications, above mentioned and have no particular bearing on my present invention. 73

A rotatable shaft 12 is adapted to be driven by the synchronizing device B, above mentioned. Attached to said shaft is a circular distributor 13 of insulating material. Said distributor carries a pawl 14 pivoted at 15 which makes contact with a platinum tip screw 16 also carried by the distributor. A post 17 carries a regulating screw 18 and a nut 19 for limiting the distance said pawl may 80 move away from its contact screw 16. 85

A small bar 20 is adapted to slide in a guide 21 fixed to the distributor 13. As shown in Fig. 2, the bar 20 is provided with a slot near the center of said distributor through which 95 the pawl 14 extends. The outer extremity of bar 20 is furnished with a small piece of insulating material as shown at 22.

A spring 23 is attached at one end of the bar 20 and its other end is fastened to a bell 100

crank 26, pivoted to distributor 13 at 27. The spring 23 normally holds members 16 and 14 separated.

The periphery of distributor 13 carries two metal contacts 24 and 25. The contact 24 is placed in electrical communication with the screw 16 while the contact 25 is electrically connected to the pivot 27 through pawl 14, spring 23 and lever 26. As shown in Fig. 3, the extremities of said contacts are arranged in overlapping relation.

Arranged concentrically with the distributor 13 is a casing 28 of insulating material and which carries two carbon brushes 29 and 30 in electrical communication with the binding posts 31, 32 fixed to said casing. As shown in Fig. 3 the brushes 29 and 30 are disposed on opposite edges of the periphery of the distributor in such a manner that the brush 29 contacts with the contact 24 on the longer portion thereof while the brush 30 can only contact with member 24 on its shorter portion. The casing 28 is closed by a cover 229 screwed thereon and at its center carries an abutment for the extremity 9 of the bell-crank lever 26. Said casing is provided with a cam member 33 which bears against the extremity 22 of the bar 20.

The mechanism above described is furnished with a pressure operated switch which comprises a coiled tube 34, connected to the storage tank T of the air compressor A by means of a pipe 35. The other extremity carries a projection 36 which engages a slot 37 on the end of a lever 38, pivoted on a stud 39. A brush 40 is attached to the other end of said lever and extends perpendicularly therefrom. The brush 40 is insulated from the lever 38 in any convenient manner or the lever 38 may be constructed of insulating material.

The brush 40 is adapted to slide over a plurality of contacts 41, 42, 43 insulated from each other and from the apparatus.

The switch is further provided with two stops 44 and 45 which limit the movement of lever 38. Said lever is provided with a sector portion disposed concentrically with respect to its pivot 39 and provided with notches 46 and 47. A ball 48 is adapted to bear against said sector portion by means of a spring 49 and a regulating screw 50 mounted in a suitable support 51.

The low tension circuit of my device includes a low voltage winding 52 of the usual spark-coil, one terminal of which is connected to the earth. The other terminal of said coil winding is connected to one of the terminals 53 of a suitable generator such as a battery 54. The other terminal of said battery 54 is connected by means of a wire 55 to the contact 41. Two conductors 56 and 57 connect the contacts 42 and 43 to binding posts 31 and 32 respectively. The shaft 12 and all the metal elements in contact therewith, namely the pawl 14 and the contact 25 are grounded.

The high tension circuit comprises simply a high tension coil 58 in inductive relation with coil 52. One terminal of coil 58 is grounded while the remaining terminal is connected to spark-plugs 60 of compressor A by means of wires 59.

The operation of my device will now be described:

Normal operation

When the air compressor is operating normally, the distributor 13 turns alternately in such a manner that the bar 20 describes an angle equal to 360° —a (Fig. 1). The position of the bar in Fig. 1 is the position occupied when the pistons of the compressor have reached the end of their stroke in their movement toward each other. The position corresponding to the other side of the angle a represents that occupied by the bar 20 when the pistons have attained the end of their stroke in the direction from each other.

When the distributor 13 starts to rotate, bar 20 moves under the action of centrifugal force and closes the contacts 14 and 16 by carrying the former contact with it.

When the pistons reach the end of their stroke, the distributor slows down and the spring 23 draws the bar 20 toward the center of the distributor carrying with it the pawl 14 and breaking the low tension circuit which extends from the ground, pawl 14, contact 16, contact 24, brush 29, binding-post 31, wire 56, contact 42, brush 40, contact 41, wire 55, battery 54, wire 53, low-tension winding 52 and thence to the ground. The rupture of the low tension circuit produces the necessary sparks for firing the motor cylinder.

When the pistons of the compressor are driven forward by the impact of the explosion thus produced, the distributor 13 is turned in the direction of the arrow 61. Rotation of the said distributor reestablishes the contact between members 14 and 16 thus closing the low tension circuit, above traced. Continued rotation brings the brush 29, which is in contact with contact 24, into electrical communication with contact 25. This changing from one contact to another has no effect on the circuit because the brush 29 is made large enough to bridge the contacts 24, 25 in passing as shown in dotted lines at 129 in Fig. 3. Before the change took place contact 24 was grounded through pawl 14 and bar 20 drawing said pawl into contact with the screw 16, which as above described, is in electrical communication with the contact 24. Since contact 25 is in electrical communication with the lever 26 on the frame of the machine which is grounded, the movement of the brush 29 from one contact to the other has no effect on the circuit whatsoever.

When the energy imparted to the pistons is spent they arrive at the end of their stroke and the bar 20 of the distributor 13 occupies

the position represented by the upper side of the angle α . The spring 23 again overcomes the centrifugal force imparted to bar 20 and opens the contacts 14, 16 as before. 5 This time, however, no spark is produced in the spark-plug 60 due to the fact that the low tension circuit has been grounded through brush 29 and contact 25 independently of the contacts 14, 16.

10 Even with the apparatus functioning normally and the distributor alternating regularly, the angle $360^\circ - \alpha$ is bound to vary slightly due to small irregularities in operation. As described more fully in my co-pending 15 application Serial No. 181,554 filed April 6, 1927, it is important that when the pistons are furthest apart the distributor should not be about to turn in the reverse direction of the arrow 61 because such a relation of the 20 parts would produce a spark when the distributor moves in said reverse direction. That is why, among other reasons, that contact 24 is made relatively long in the direction opposite to arrow 61 with respect to brush 29.

25 It will be obvious to those skilled in the art from the foregoing that should the distributor be over-thrown in the direction opposite to the arrow 61 it becomes necessary to stabilize the apparatus and the spark must be given 30 even though the spring 23 is unable to overcome the centrifugal force of bar 20. The firing of the cylinder is assured by the cam 33 at a certain predetermined position of the distributor which raises the bar 20 upon over-throw of the distributor and breaks the low-tension circuit. This is the reason why the 35 contact 24 is extended beyond brush 29 in the direction of the arrow 61.

In order to regulate the output of the 40 compressor or simply to run the compressor abnormally, it is necessary to provide a means for advancing and retarding the spark. For this purpose the cover 229 screwed to the casing 28 bears against the extremity 9 of lever 45 26 and regulates the tension of spring 23 according to the position it occupies. The greater the tension of spring 23 the sooner it can overcome the centrifugal force of bar 20 and hence the sooner the low tension circuit 50 will be interrupted and vice-versa. In short, screwing the cover 29 on the casing 28 advances the spark and unscrewing said cover retards it.

Operation during idling

55 As shown in Fig. 4 the tube 34 is attached to the storage tank T of the compressor a by means of pipe 35. When the pressure in said tank T is below normal, the tube 34 is relaxed and the switch lever remains in the position shown in Fig. 1, which position was assumed for the explanation of the normal operation 60 of the apparatus. As the pressure in the storage tank T comes up to normal the tube 65 comes affected thereby and tends to unwind.

This movement tends to move the lever 38, in contact with the stop 44, against the stop 45. But this force tending to move said lever is opposed by the ball 48 held in notch 47 by the spring 49. When the force tending to move lever 38 becomes sufficient to overcome the pressure exerted against the ball by spring 49, the lever is abruptly thrown from the stop 44 to the stop 45. The pressure exerted by the spring 49 may be varied by turning the regulating screw 50 and hence the lever 38 may be made to move when the pressure in the storage tank T has attained any value desired. 70 75

The brush 40 is made large enough so that the low-tension circuit is not broken when it passes from contact 42 to 43 during movement of said brush across the space between said contacts. 80

When the switch has moved to contact 43 the low-tension circuit is established from the ground to pawl 14, contact 16, contact 24, brush 30, binding-post 32, wire 57, contact 43, brush 40, wire 55 etc. to ground, or the circuit may be formed from the ground to contact 25, brush 30, binding-post 32, wire 57, contact 43, 85 brush 40 etc. to ground depending on the position of the distributor 13. The brush 29 is thus taken from its circuit and replaced by the brush 30. 90

Suppose that lever 38 has been moved at 95 the time the distributor 13 is moving in a direction opposite to that of the arrow 61, that is, during the period of compression of the explosive mixture in the motor cylinder, the distributor slows down toward the end 100 of its throw and the contacts 14, 16 are opened as before explained. But since the low tension circuit is established through the grounded contact 25 independently of contacts 14 and 16, the opening of said contacts has no effect 105 thereon and no spark is produced in the motor cylinder.

From the foregoing it will be obvious that as the pistons move away from each other the distributor 13 is turned in the direction 110 of the arrow 61, but since the pistons have received no energy they are unable to compress the air in their respective cylinders. The stroke of the pistons, therefore becomes less than normal and are unable to uncover 115 the admission and exhaust openings.

As a result the movement of distributor 13 is considerably reduced and the angle α consequently grows larger. No spark, however is produced during opening of contacts 14, 16 120 due to the particular arrangement of the brushes 29, 30 with respect to the overlapping contacts 24, 25, the brush 30 being always on the grounded contact 25 when said opening takes place. 125

The parts are so arranged that when the pistons start to idle there is always an explosive mixture between them which is just sufficient to drive the pistons to the normal end of their stroke. The pistons continue to 130

reciprocate slower and slower compressing the explosive mixture between them over and over again.

It will be noted that during this reciprocation of the pistons the brush 30 passes completely over the overlapping portion of contact 24 in its path and that when the distributor reverses its direction of motion said brush is always in contact with 25. As the reciprocations of the pistons become sufficiently reduced the movement of the distributor also becomes reduced in proportion. There finally arrives a condition where the brush 30 no longer moves over on contact 25 when the distributor reverses its motion in the direction of the arrow 61, but remains on contact 24 until the motion is reversed. This places the contacts 14, 16 again in the low tension circuit and when said contacts are opened by the spring 23 a spark is produced in the plug 60 in a manner already described. The pistons are driven in opposite directions by the force of the explosion with sufficient energy to assure scavenging of the cylinders and the evacuation of the burned gases as well as the introduction of a fresh charge of explosive mixture in the cylinder. At the same time the movement of the distributor becomes increased to that which it was when the compressor started to idle. The pistons again start to reciprocate slower and slower and the same cycle of operations, above described, is repeated. The device continues to operate lightly with only sufficient energy to keep it in motion as long as the pressure remains normal in the storage tank.

Resumption of load

When the pressure of the air in the storage tank T drops below normal, the coiled tube 34 again relaxes and moves the lever 38 from the stop 45 to the stop 44, the ball 48 causing an abrupt action when moving from notch 46 to notch 47 as before. The brush 40 is thus moved from the contact 43 back to the contact 42 and reestablishes the low-tension circuit through the brush 29 as already described. As soon as the distributor 13 moves in the direction opposite to that of arrow 61, the charge of explosive mixture immediately becomes ignited upon the distributor slowing down as previously described. The compressor A then takes on load and continues to operate until the pressure in the storage tank T is built up to normal.

In order to make sure that the brush 29 will be on the contact 24 when the distributor 13 has completed its movement opposite to that of the arrow 61, the angular sector included by the contact 24 is made greater than the angle included between the two brushes 29 and 30. With this arrangement no matter how small the oscillations of the distributor 65 may become they cannot descend beyond a

certain limit determined by the position of brush 30 with respect to contact 24. The brush 29 will always, therefore, be on contact 24 as soon as the distributor starts to move in the direction opposite to the arrow 61.

The pistons C pick up the load very rapidly and reciprocate the full length of their stroke as soon as the switch lever 38 operates.

The instrumentalities employed for admitting an explosive mixture into the compressor A and for producing the exhaust thereof after firing has not been disclosed since such means are well known by those skilled in the art and are not essential to an understanding of my invention as comprehended within the scope of the appended claims. The same observation is true of the inlet and outlet valves of the compressing cylinders.

Many variations in my apparatus may be made by those skilled in the art without departing from my invention, since

What I claim is—

1. An ignition device for motor compressors having free-flying direct acting pistons interconnected by a non-kinematic oscillating stabilizing mechanism comprising a closed ignition circuit, means for normally opening said ignition circuit at regular intervals driven by an element of said stabilizing mechanism and means for automatically changing the intervals at which said circuit is opened.

2. An ignition device for motor compressors having free-flying direct acting pistons interconnected by a non-kinematic oscillating stabilizing mechanism comprising a closed ignition circuit, means driven by an element of said stabilizing mechanism for normally opening said ignition circuit at regular intervals and means responsive to the pressure of the fluid compressed for automatically changing the intervals at which said circuit is opened.

3. An ignition device for motor compressors having free-flying direct acting pistons interconnected by a non-kinematic oscillating stabilizing mechanism comprising means driven by an element of said stabilizing mechanism for supplying a spark to the motor cylinder at regular intervals during operation under load and means for automatically suppressing certain of the sparks when said compressor starts to idle.

4. An ignition device for motor compressors having free-flying direct acting pistons interconnected by a non-kinematic oscillating stabilizing mechanism comprising a centrifugally operated distributor driven by an element of said stabilizing mechanism for supplying a spark to the motor cylinder at regular intervals during operation under load and pressure operated means for automatically suppressing certain of the sparks when said compressor starts to idle.

5. An ignition device for motor compressors

5 sors having free-flying direct acting pistons interconnected by a non-kinematic oscillating stabilizing mechanism comprising a centrifugally operated distributor adapted to be oscillated through an angle less than 360° by an element of said stabilizing mechanism, an ignition circuit connected to said distributor and means on said distributor for opening said ignition circuit when said distributor 10 changes its direction of rotation and for rendering one of said opening operations ineffective.

6. An ignition device for motor compressors having free-flying direct acting pistons interconnected by a non-kinematic oscillating stabilizing mechanism comprising a centrifugally operated distributor driven by an element of said stabilizing mechanism, a working circuit controlled by said distributor, an idling circuit controlled by said distributor, a main ignition circuit and means for connecting said working circuit during operation under load to said ignition circuit and for replacing said working circuit by 25 said idling circuit during periods of idling.

7. An ignition device for motor compressors having free-flying direct acting pistons interconnected by a non-kinematic oscillating stabilizing mechanism comprising a 30 coiled tube adapted to respond to variations in pressure of the compressed fluid supplied by the compressor, a switch lever operated by said tube, means associated with said switch lever to cause the same to move abruptly, a main ignition circuit extending from said switch lever to the ground, a plurality of contacts associated with said switch lever, a normal working circuit connected to one of said contacts, an idling circuit connected 35 to the other of said contacts, a distributor, brushes on said distributor, means for connecting said brushes to said working circuit and to said idling circuit respectively, means on said distributor for producing sparks at 40 regular intervals when connected to said working circuit and for suppressing certain of said sparks when connected to said idling circuit and a ground connection for said last mentioned means.

50 8. In an ignition device for motor compressors having free-flying direct acting pistons interconnected by a non-kinematic oscillating stabilizing mechanism, a distributor comprising an operating shaft driven by an element of said stabilizing mechanism, an insulating contact drum on said shaft, contacts carried by said drum, a brush associated with said contacts, a pivotally mounted contact pawl connected to one of said contacts on said drum, a stationary contact on said drum connected to the other of said first mentioned contacts associated with said pawl, centrifugally operated means for moving said pawl into engagement with said 55 stationary contact during oscillation of said

drum, means for moving said pawl away from said stationary contact during reversal of said drum and means associated with said pawl and said contacts for rendering certain of the circuit opening movements of 70 said pawl electrically inoperative.

9. In an ignition device for motor compressors having free-flying direct acting pistons interconnected by a non-kinematic oscillating stabilizing mechanism, a distributor 75 comprising an operating shaft driven by an element of said stabilizing mechanism, an insulating contact drum on said shaft, contacts carried by said drum, a plurality of brushes associated with said contacts, a pivotally mounted contact pawl connected to one of said contacts on said drum, a stationary contact on said drum connected to the other of said first mentioned contacts associated with said pawl, centrifugally operated means for moving said pawl into engagement with said stationary contact during oscillation of said drum, means for moving said pawl away from said stationary contact during reversal of said drum and means associated with said pawl and said contacts for rendering certain of the circuit opening movements of 85 said pawl electrically inoperative at relatively different intervals with respect to said brushes. 90

10. In an ignition device for motor compressors having free-flying direct acting pistons interconnected by a non-kinematic oscillating stabilizing mechanism, a distributor comprising an operating shaft driven by an element of said stabilizing mechanism, an insulating contact drum on said shaft, a centrifugally closed interrupter on said drum, means for automatically opening said interrupter during reversal of said drum, means for automatically rendering certain of said opening operations electrically ineffective and means for assuring the opening of said interrupter in the event of an abnormal oscillation of said drum. 100 105 110

11. In an ignition device for motor compressors having free-flying direct acting pistons interconnected by a non-kinematic oscillating stabilizing mechanism, a distributor comprising an operating shaft driven by an element of said stabilizing mechanism, an insulating contact drum on said shaft, a fixed contact on said drum, a pivotally mounted contact associated with said fixed contact, a slidably mounted bar on said drum engaging said pivotal contact at right angles thereto, a spring opposing the centrifugal movement of said bar, means for automatically rendering certain of the opening operations of said contacts electrically ineffective and a fixed cam associated with said bar for assuring the opening of said contacts in the event of an abnormal oscillation of said drum. 115 120 125

12. In a distributor of the type described 130

a contact pawl, a centrifugal member operatively associated with said pawl and adapted to be moved in one direction by centrifugal force and in the other direction by a 5 spring, a bell-crank having one arm attached to said spring, an insulated casing for said distributor and a screw cover for said casing adapted to bear against the other arm of said bell-crank whereby the position of said cover 10 on said casing determines the amount of tension in said spring.

13. In a distributor of the type described a casing of insulating material, a cover screwed on said casing and means operated 15 by the rotation of said cover for advancing and retarding the spark produced by said distributor.

14. In a device of the class described a distributor comprising a drum of insulating 20 material, means on said drum for opening an ignition circuit at regular intervals, a pair of contacts extending around the periphery of said drum, two adjacent edges of said contacts being arranged parallel to each other 25 and to the axis of the drum, the other two adjacent edges being arranged in over-lapping relation, a pair of brushes associated with said contacts disposed on opposite sides of said drum and means for placing said first 30 mentioned means into electrical communication with said contacts and a ground connection for said first mentioned means whereby the ignition circuit may be opened at regular intervals through one of said brushes and 35 at different regular intervals through the other of said brushes.

15. In a device of the class described a distributor comprising a drum of insulating material, means on said drum for opening an 40 ignition circuit at regular intervals, a pair of contacts extending around the periphery of said drum, two adjacent edges of said contacts being arranged parallel to each other and to the axis of the drum, the other two adjacent 45 edges being arranged in overlapping relation, a pair of brushes associated with said contacts disposed on opposite sides of said drum means for placing said first mentioned means into electrical communication 50 with said contacts, a ground connection for said first mentioned means whereby the ignition circuit may be opened at regular intervals through one of said brushes and at different regular intervals through the other 55 of said brushes and means operated by the pressure of the fluid compressed by the compressor for rendering one of said brushes operative when the compressor is operating under load and the other of said brushes operative 60 when said compressor starts to idle respectively.

16. An ignition device for motor compressors having free-flying direct acting pistons interconnected by a non-kinematic oscillating 65 stabilizing mechanism comprising a centrifu-

gally operated distributor driven by an element of said stabilizing mechanism for supplying a spark to the motor cylinder at regular intervals during operation under load, means responsive to the pressure of the fluid compressed for suppressing certain of the sparks when said compressor starts to idle, a casing of insulating material for said distributor, a cover screwed on said casing and means operated by the rotation of said cover for advancing and retarding the spark produced by said distributor.

In testimony whereof, I have signed my name to this specification at Barcelona, Spain, this 24th day of March, 1927.

RAUL PATERAS PESCARA.
